UNITED STATES PATENT OFFICE.

JAMES E. WILSON, OF NEW YORK, N. Y.

PYROMETER.

1,046,925.

Specification of Letters Patent. Patented Dec. 10, 1912.

Application filed September 7, 1912. Serial No. 719,192.

To all whom it may concern:

Be it known that I, JAMES E. WILSON, a citizen of the United States, residing in the city of New York, county of New York, and State of New York, have invented certain new and useful Improvements in Pyrometers; and I do declare the following to be a full, clear, and exact description of the invention, such as will enable others skilled in the art to which it appertains to make and use the same.

This invention relates to the subject of pyrometers, and it has particularly in view a novel type of thermo-electric pyrometer and associated mechanism whereby the same can be readily applied to a rotary furnace to positively and accurately indicate the internal temperature of the said furnace.

The improved pyrometer as aforesaid is of special utility in connection with the type of rotary furnaces that are used in annealing and hardening small products, and in the accompanying drawings so much of that type of furnace has been shown as is sufficient to give a thorough understanding of the operation of the invention, but, of course, it will be readily appreciated that the invention is not limited to the type of furnace shown.

Referring to the accompanying drawings wherein like characters of reference designate corresponding parts, Figure 1 is a view in front elevation of a rotary furnace equipped with the improved pyrometer. Fig. 2 is a view in side elevation thereof. Fig. 3 is a fragmentary plan view, showing the manner of mounting the slip rings which form an important feature of the invention. Fig. 4 is a sectional view taken on the line 3—3, Fig. 4. Fig. 5 is a detail sectional view of the brushes and supports therefor which coöperate with the rings shown in Figs. 3 and 4. Figs. 6 and 7 are views corresponding to Figs. 1 and 2, but illustrating a modification of the invention.

The improved thermo-electric pyrometer has been shown in connection with a rotary furnace, the furnace being designated by the numeral 1, and being shown conveniently for the reason that the invention relates solely to pyrometers and is not at all dependent upon any particular type of furnace. The furnace, as shown, is of the internally fired type, such as is used for hardening and annealing small products.

The pyrometer includes in its general organization a plurality of angular brackets 2 which, in the form of the invention shown in Figs. 1 and 2 of the accompanying drawings, are fastened in regularly spaced radiating relation to the outer surface of the rotatable portion of the furnace 1, the angular type of brackets being preferred as they provide the outwardly projecting flat portions 2^a which form supports for the blocks 3 of insulating material 3, said insulating material being preferably detachably fastened to the supporting portions 2^a of the brackets 2 by the screws 4. Slip rings 5 surround and seat upon the insulating blocks 3, said rings being detachably fastened thereto by suitable means such as the bolts 6 and nuts 7. It will be observed by referring to Figs. 1, 2, and 3 of the accompanying drawings, that the brackets support the rings 5 in spaced radiating relation to the furnace 1, and that said rings are also retained in spaced parallel relation upon said brackets.

A bracket 8 is carried by the base, or foundation 9, of the furnace 1, said bracket projecting outwardly beyond the rings 5 and having a vertical arm 10 that parallels, in spaced relation, said rings. The bracket 8 is so disposed that its vertical arm 10 terminates adjacent the peripheries of rings 5, and from the upper end of said arm, a non-conducting rod 11 projects laterally. The rod 11 may be formed of vulcanized fiber or other material that is a nonconductor of electricity, and said rod overlaps, in spaced relation, a portion of the peripheries of rings 5. Sleeves 12 are mounted on the rod 11 in spaced relation. Each sleeve 12 has a shoulder 13 at one end, and at the other end has an abutment band 14, the bands being held to the sleeves by the set screws 15, or other convenient fastening means, and such fasteners may also serve to lock the sleeves to the rod 11. Brush holders 16 are loosely mounted on the sleeves 12 and have the brushes 17 held therein by means of the set screws 18. The brushes project toward and their free ends contact with the peripheries of rings 5. Springs 19 are coiled about the sleeves 12, said springs having their ends connected to the bands 14 and the holders 17, and said springs obviously permit resilient movements of the holders 16 relative to the sleeves 12.

A fire-resisting tube 20 extends within the

- furnace 1 and has one end projecting beyond the exterior of said furnace. The projecting outer end of tube 20 is open, as indicated at 21, and one portion of a thermo-couple 22 is suitably housed therein. The thermo-couple projects outwardly beyond the open end of tube 20 and has circuit connections 23—24 with binding posts 25 carried by the rings 5.
- 10 A galvanometer 26 has circuit connections 27—28 with the brush-holders 17. From the foregoing description it will be understood that the rings 5 being in circuit with the pyrometer and rotating with the furnace, the circuit is through said rings, brushes 17, circuit connections 27—28, and the galvanometer, and owing to the described arrangement of the brushes relative to the rings 5, the said galvanometer is at all times in circuit with the pyrometer, thereby causing a prompt and accurate indicating of the temperature of the furnace.
- To assure an accurate reading of the temperature of a rotating furnace it is essential that the furnace must, at all times be in constant electrical communication with the galvanometer, and in practice it has been found that the use of the slip rings 5 and the co-operating stationary brushes 17 efficiently serve as the circuit closing means; but it will be apparent that modifications as to structural arrangements and details of constructions may be resorted to in this respect. For instance, as suggested in Figs. 6 and 7 of the accompanying drawings, a supporting frame may be carried by the foundation 9 of the furnace, said frame being designated by the numeral 29 and having a vertical portion 30 that parallels, in spaced relation, 25 of front of the furnace, said vertical portion being preferably in the form of an arch and equipped with inwardly projecting lateral angular brackets 31 which rigidly support rings 32 in spaced relation, insulating blocks 33 being interposed between the rings and brackets. In this form of the invention, the thermo-couple has circuit connections 34—35 with brushes 36 carried by an insulated rod 37, the rod being carried by the furnace 1. Binding posts 38 carried by the stationary rings 32 have circuit connections 39—40 with the galvanometer. As will be clear, the only vital difference between the latter form of the invention and the first-described form is that in the latter the rings are stationary and the brushes are movable, while in the first instance, the rings are movable and the brushes stationary.
- While two forms of the invention have been described in detail, it is to be understood that such are forms that have been found to be practical and efficient and that the same serve as examples of the practical working of the invention; but it is to be understood that the invention in its broad

aspect contemplates changes in details and structural arrangements, such as fall within the scope of the appended claims.

What I claim as my invention is:—

1. The combination with a rotatable furnace, of a plurality of brackets carried thereby and arranged in radiating relation, slip rings carried by and retained in spaced relation to the furnace by said brackets, means for insulating the rings from the brackets, a pyrometer carried by the furnace, circuit connections between the pyrometer and the rings, stationary brushes engaging the rings, a temperature indicator, and circuit connections between the indicator and the brushes. 70

2. In a rotary furnace, a thermo-electric pyrometer comprising independently insulated ring and brush elements in contact with each other, one of which is carried by the revolving furnace while the other is stationary, means for spacing the furnace carried element from the furnace, a thermo-couple extending within the furnace and carried thereby, and connections between 85 said couple and element carried by the furnace, a galvanometer, and connections between the galvanometer and the stationary element. 80

3. In a rotary furnace, a thermo-couple 95 carried thereby, independently insulated rings carried by the furnace and supported in spaced relation to the same, independently insulated brushes in contact with said rings, a stationary support for the brushes, 100 a galvanometer, connections between said rings and said couple, and connections between the brushes and galvanometer.

4. In a rotary furnace, a thermo-electric pyrometer comprising independently insulated contact and brush elements, one of which is carried by the revolving furnace while the other is stationary, a galvanometer, means for retaining the furnace carried element in spaced relation to the furnace, a thermo-couple extending within said furnace and carried thereby, and connections between said couple and element carried by the revolving furnace and between said galvanometer and stationary element. 110

5. The combination with a rotatable furnace, a thermo-couple carried thereby, slip rings retained in spaced relation to the furnace, circuit connections between the rings and the couple, a stationary support, brushes carried thereby and engaging the rings, a galvanometer, and circuit connections between the galvanometer and the brushes. 120

6. In a rotary furnace, a thermo-electric pyrometer comprising independently insulated contact surfaces carried by and supported in spaced relation to said furnace, independently insulated brushes in contact with said contact surfaces and supported by a stationary element, a galvanometer, and 125 130

circuit connections between the brushes and the galvanometer.

7. In a rotary furnace, said furnace having a thermo-couple, a plurality of angular brackets carried by the furnace and providing outwardly projecting supports, said brackets being arranged in radiating relation, insulating blocks carried by each support, slip rings arranged in spaced parallel relation and seated on said insulating blocks, said rings being retained in spaced relation to the furnace by the supports, circuit connections between the rings and the couple, a stationary support, brushes carried thereby and engaging the rings, a galvanometer, and circuit connections between the brushes and galvanometer.

8. In a rotary furnace, a thermo-electric pyrometer carried thereby, contact surfaces carried by the furnace and in circuit with the pyrometer, a stationary support provided with a vertical extension that overlaps the contact surfaces in spaced relation, brushes carried by extension of the support and engaging the contact surfaces, a galvanometer, and circuit connections between the brushes and the galvanometer.

In testimony whereof I affix my signature in presence of two witnesses.

JAMES E. WILSON.
